UNITED STATES PATENT OFFICE.

WILLIAM J. CARROLL, OF NEW HAVEN, CONNECTICUT, ASSIGNOR TO SARGENT & COMPANY, OF NEW HAVEN, CONNECTICUT, A CORPORATION OF CONNECTICUT.

LOCK.

No. 903,839.

Specification of Letters Patent.

Patented Nov. 17, 1908.

Application filed May 25, 1906. Serial No. 318,733.

To all whom it may concern:

Be it known that I, WILLIAM J. CARROLL, of the city and county of New Haven and State of Connecticut, have invented new and useful improvements in Locks, of which the following is a full, clear, and exact description when taken in connection with the accompanying drawings, which form a part thereof, and in which—

10 Figure 1 represents a side elevation of a lock (with the cap plate removed) embodying the invention, Fig. 2, a similar view of the upper portion of the lock, with the latch bolt shown locked in its retracted position, Fig. 3, a similar view with the latch bolt and key bolt shown protracted, Fig. 4, a similar view of the lock, with the latch bolt and key bolt shown retracted, Fig. 5, a reverse view of the parts shown in Fig. 2, and Fig. 6, a 20 detailed view of the locking dog.

In all figures, similar letters of reference represent like parts.

This invention relates to locks, and more particularly to locks for use on doors of stores, and similar places, wherein a thumb piece is provided to operate the latch bolt.

The object of the invention is the production of a lock having novel means for locking the latch bolt in its retracted position, so that the latch bolt may be held retracted during business hours, and the door may be opened without the necessity of operating the latch bolt by the thumb piece. When, however, the key bolt is protracted the latch bolt is released from engagement by the locking dog, so that it will be protracted by its spring.

To this, and other ends, the invention consists of the improvements and combinations of parts set forth and claimed hereinafter.

Referring to the drawings for a more particular description of the invention, the parts designated by the letter A represent the casing of the lock, and B its face plate, 45 through which are adapted to project the latch bolt C and key bolt D. The latch bolt at its rear is pivotally connected to a stud E, on a lever F, pivotally mounted on a post G in the casing.

50 A spring H engages the lever F and the casing to normally hold the lever in the position shown in Figs. 1 and 3, wherein the latch bolt is shown protracted. An actuating bar I is adapted to be engaged on its under edge J by a thumb piece (not shown), and when

the bar I is forced upward, as shown in Fig. 4, its upper end will engage a depending stud K on the under side of the lever F (Fig. 5) to rotate the lever F against the tension of the spring H and retract the latch bolt. A 60 flat spring L is shown bearing upon the actuating bar to hold it in its lower position (Fig. 1).

The key bolt D is provided with a tumbler M of any desired construction, and the key bolt and tumbler are adapted to be operated by the bit N of a cylinder lock O (Figs. 3 and 4), in usual manner.

Pivoted to a depending stud P on the under side of the key bolt D (Fig. 5) is a dog R, one end of which S projects into the path of rotation of the bit N of the cylinder lock O when the key bolt D is in its retracted position (Figs. 1, 2, 4 and 5). The dog R is provided with a finger T and shoulder 75 or stop U on the under side of the finger. When the dog is swung by the bit N of the cylinder lock O into the position shown in Figs. 2 and 5, the finger T will engage a depending stud V on the under side of the 80 lever F (Fig. 5) and rotate the lever to retract the latch bolt. When the latch bolt is thus retracted, and the pressure of the bit N on the dog R released, the spring H will tend to turn the lever F to protract the latch bolt, but the stud V will abut against the stop U, and this engagement will act as a toggle to prevent the rotation of the dog R on its pivot P, and the lever F on its pivot G. In this way, when the key bolt is retracted, by the rotation of the bit of the cylinder lock from the position shown in Fig. 1 to that shown in Fig. 2, the latch bolt 85 C is retracted and is held in its retracted position. This may be done upon the opening of the store, or other building, for business in the morning, and the latch bolt will remain retracted, so that the door may then be opened during business hours without the necessity of using the thumb piece and actuating bar I.

When the key bolt D is protracted by the bit N of the cylinder lock O, as the dog R is mounted thereon it is carried forward into the position shown in Fig. 3, and the stud V 105 is disengaged from the stop U, so that the lever F may be rotated by the action of the spring H to protract the latch bolt. Thus the locking of the door at night, or at other times, will release the latch bolt, so that it 110

- will be protracted. Furthermore, the dog R is also provided with a projection W which when the key bolt is protracted (as shown in Fig. 3) bears on its under side against a post X in the casing, and on the opposite side engages the depending stud V on the under side of the lever F and prevents the rotation of the lever F and the retraction of the latch bolt when the key bolt D is thus protracted.
- 10 Thus the latch bolt is locked against retraction when the key bolt is protracted.

When the bit N of the cylinder lock O is rotated to engage the tumbler M and key bolt D to retract it (Fig. 3), it does not come 15 in contact with the end S of the dog R, as the dog has been moved forward out of the path of the bit. Hence the bit N will retract the key bolt without operating the dog R to retract the latch bolt, but after the key 20 bolt is retracted, further rotation of the bit N will operate the dog R to retract the latch bolt, as above described.

When the key bolt is retracted, the latch bolt may be retracted by the actuating bar I, 25 as shown in Fig. 4, without the stud V engaging the stop U of the dog R, because a spring Y on the dog R engages, as shown more particularly in Fig. 5, the key bolt to hold the dog normally in the position shown 30 in Fig. 1, so that the finger is held away from the stud V. Upon the rotation of the lever F by the actuating bar I, the stud V bears on the upper side of the projection W of the dog R, but the finger T and stop U 35 are held away from it by the spring Y.

Having now described my invention (which may vary in its details without departing from the spirit thereof), what I claim and desire to secure by Letters Patent, 40 is:—

1. In a lock, the combination with a case; of a latch bolt movable in said case and yieldingly held in its protracted position; means for retracting said latch bolt; and mechanism operated by a key adapted to engage said latch bolt retracting means to lock said latch bolt in its retracted position, substantially as described.

2. In a lock, the combination with a case; 50 of a latch bolt movable in said case; a key bolt also movable in said case; pivoted mechanism for locking said latch bolt in its retracted position released upon the protraction of said key bolt; and means for operating said latch locking mechanism substantially as described.

3. In a lock, the combination with a case; of a latch bolt movable in said case; a key bolt also movable in said case; pivoted mechanism for locking said latch bolt in its retracted position released upon the protraction of said key bolt, substantially as described.

4. In a lock, the combination with a case; 60 of a latch bolt movable in said case; a key

bolt also movable in said case; pivoted mechanism for locking said latch bolt in its retracted position when said key bolt is in its retracted position; and means for operating said latch locking mechanism, substantially 70 as described.

5. In a lock, the combination with a case; of a latch bolt movable in said case; a key bolt also movable in said case; and mechanism pivotally mounted on said key bolt for 75 locking said latch bolt in its retracted position, substantially as described.

6. In a lock, the combination with a case; of a latch bolt movable in said case; a key bolt also movable in said case; separate pivoted mechanism for locking said latch bolt in its retracted position operated by the key of said key bolt, substantially as described.

7. In a lock, the combination with a case; of a latch bolt movable in said case; means 80 for retracting said latch bolt; a cylinder lock in said case; a lever operated by said cylinder lock and adapted to engage said latch bolt retracting means to lock said latch bolt in its retracted position, substantially as de- 90 scribed.

8. In a lock, the combination with a case; of a latch bolt movable in said case; a key bolt also movable in said case; a cylinder lock adapted to operate said key bolt; and 95 a lever fulcrumed on said key bolt and operated by said cylinder lock to lock said latch bolt in its retracted position, substantially as described.

9. In a lock, the combination with a case; 100 of a latch bolt movable in said case; a key bolt also movable in said case; means for retracting said latch bolt independent of the key of said key bolt; and mechanism pivotally mounted on said key bolt adapted to 105 engage said latch retracting means upon the protraction of said key bolt to prevent its operation, substantially as described.

10. In a lock, the combination with a case; of a latch bolt movable in said case; a key 110 bolt also movable in said case; and a lever adapted to be operated by the key of said key bolt when in its retracted position to lock said latch bolt in its retracted position, and carried free from the operation by said key when said key bolt is protracted, substantially as described.

11. In a lock, the combination with a case; of a latch bolt movable in said case; a key bolt also movable in said case; and a lever 120 fulcrumed on said key bolt, and adapted to be operated by the key of said key bolt when in its retracted position to lock said latch bolt in its retracted position and upon the protraction of said key bolt adapted to lock 125 said latch bolt in its protracted position, substantially as described.

12. In a lock, the combination with a case; of a latch bolt movable in said case; a lever for retracting said latch bolt pivotally 130

mounted on said case; and pivoted mechanism operated by a key adapted to engage said lever to hold said latch bolt in its retracted position, substantially as described.

5 13. In a lock, the combination with a case; of a latch bolt movable in said case; a lever for retracting said latch bolt pivotally mounted on said case; mechanism operated by a key adapted to engage said lever to 10 hold said latch bolt in its retracted position;

and means for operating said lever independent of said key, substantially as described.

In witness whereof, I have hereunto set my hand on the 24th day of May, 1906.

WILLIAM J. CARROLL.
